PAINTBRUSH PRESS

Leah V. Hook, Middletown, Ohio

Application November 1, 1947, Serial No. 783,591

3 Claims. (Cl. 211—7)

1

This invention relates to a paint brush press and more particularly to a press for preserving the shape of artists' brushes between periods of use.

The paint brushes of various sizes used by artists are made of very fine materials and are quite expensive. When the artist cleans his brushes after a period of use and lays them aside, the hairs tend to flare outward so that when they are used the next time they are apt to produce fuzzy edges.

In view of the high price of these brushes, it is desirable that their shape be preserved between periods of use, and it is the primary object of my invention to provide a device in which such brushes may be kept between periods of use, which device will serve to maintain the shape of the brushes so as to avoid any objection due to fuzzy edges.

It is a further object of my invention to provide a device as above outlined which will be extremely simple in construction and inexpensive to manufacture.

These and other objects of my invention which I shall point out in more detail hereafter, or which will appear to one skilled in the art upon reading these specifications, I accomplish by that certain construction and arrangement of parts of which I shall now describe an exemplary embodiment.

Reference is made to the drawings forming a part hereof and in which:

Figure 1 is a plan view of a device according to my invention.

Figure 2 is a side elevation thereof.

Figure 3 is an end elevation thereof.

Figure 4 is a cross sectional view taken on the line 4—4 of Figure 2, and

Figure 5 is a general perspective view of the device showing the manner of use.

Briefly in the practice of my invention, I provide a frame including a brush support and a handle support which supports are parts of the frame, and in connection with the brush support I provide a clamping member hinged to the frame which may be brought into a position to overlie the brush support and be releasably secured thereto.

Referring more particularly to the drawings, I have shown a frame having the longitudinal elements 10 which constitute the handle supports and the transverse end elements 11 which hold them in spaced relation parallel to each other. The frame constituted by the members 10 and 11 may be provided with the gusset members 12

2

to give additional strength to the frame, and the frame may, if desired, be provided with feet 13, at its corners.

Substantially centrally and longitudinally of the frame I provide a brush support member indicated in the several views at 14. The member 14 is parallel to the members 10 and extends the length of the frame between the members 11. It will be understood that the device may be made of wood as shown in the drawings, and that the various frame elements may be secured together by wood screws or by means of a suitable adhesive. The device could, of course, be made of metal and the parts could be welded, riveted or otherwise suitably secured together.

I provide clamping members 15 hinged to the frame members 11 as at 16, and the members 15

are arranged in one position to overlie the brush support 14. Means are provided for releasably

securing the clamping members 15 in clamping relation to the support 14. Various such means may be provided, and I have shown by way of example, the screws 17 secured to the brush support 14 and provided with the wing nuts 18.

The clamping members 15 are provided with suitably enlarged apertures 19 to accommodate the screws 17.

It will be noted that the brush support member 14 is disposed at a slightly lower level in the frame than the handle supports 10. In use a number of brushes indicated generally at 20,

are placed in the frame as shown in Figure 5 with the brush portions resting on the brush support 14 and the handles resting on the handle support 10.

The hinged clamping member 15 is then brought down over the screw 17 and the wing nut is screwed on. Any desired degree of pressure may be obtained by the degree to which the wing nut is tightened.

As will be clear from Figure 5, a considerable number of paint brushes may thus be taken care of. It will also be clear that if the artist desires to preserve a number of brushes of different sizes, he will place the smaller brushes near the hinge

point and graduate them in size with the largest brush adjacent the screws 17. In clamping the clamping member in place, it will be observed that the clamping member will be disposed at a slight angle in relation to the brush support, and that a number of brushes of graduated size may thus be subjected to equal pressures.

It will, of course, be clear that if it were desired to preserve a series of brushes all of which were of the same size, the brush support 14 could be disposed somewhat lower in the frame, and

then when the clamping member is in position to clamp the brush, it will be disposed substantially parallel to the brush support.

I have found that if artists' brushes after a period of use, are thoroughly cleaned and then disposed in a brush press according to my invention, their shape is perfectly preserved, and when they are taken up for use they will be in as perfect condition as they were when new.

It will be clear that numerous modifications will suggest themselves to those skilled in the art, and that many such modifications may be made without departing from the spirit of my invention. I therefore do not intend to limit myself except as set forth in the claims which follow.

Having now fully described my invention, what I claim as new and desire to secure by Letters Patent is:

1. A device for preserving the shape of artists' brushes between periods of use, comprising a four sided frame including a brush support and a handle support, said supports being spaced parallel frame members, said handle support comprising one side of said four sided frame, and said brush support being disposed centrally of said frame and at a lower level in said frame than said handle support, said supports being so arranged as to maintain brushes placed thereon in a substantially horizontal position, and a clamping member hinged to said frame and arranged in one position to overlie said brush support, and means for releasably securing the free end of said clamping member to said brush support.

2. A device for preserving the shape of artists' brushes between periods of use, comprising a four sided frame including a brush support and a handle support, said supports being spaced parallel frame members, said handle support comprising one side of said four sided frame, and said brush support being disposed centrally of

said frame and at a lower level in said frame than said handle support, said supports being so arranged as to maintain brushes placed thereon in a substantially horizontal position, and a clamping member hinged to said frame and arranged in one position to lie upon said brush support in contact therewith throughout its length, and means for releasably securing the free end of said clamping member to said brush support.

3. A device for preserving the shape of artists' brushes between periods of use, comprising a four sided frame including a brush support and a handle support, said supports being spaced parallel frame members, said handle support comprising one side of said four sided frame, and said brush support being disposed centrally of said frame and at a lower level in said frame than said handle support, said supports being so arranged as to maintain brushes placed thereon in a substantially horizontal position, and a clamping member hinged to said frame in a position in which the hinged end thereof is held out of contact with said brush support, and means for releasably securing the free end of said clamping member to said brush support.
